UNITED STATES PATENT OFFICE.

JOHN DECKER, OF NEW YORK, N. Y.

LOCK.

Application filed September 20, 1921. Serial No. 502,055.

To all whom it may concern:

Be it known that I, JOHN DECKER, a citizen of the United States, residing at New York city, borough of Bronx, county of Bronx, and State of New York, have invented a certain new and useful Lock, of which the following is a specification.

This invention is a lock adapted for use on hinge doors, and the object of the invention is to provide a strong, durable and burglar-proof lock of exceptional simplicity.

The lock, generally speaking, embodies two cooperating structures, namely, a keeper adapted to be mounted on the door frame for cooperation with a lock casing mounted on the associated door and constructed to house the lock parts, intended for co-action with the keeper to lock the door in closed position and the lock operating parts by means of which the keeper may be engaged or disengaged, either through the use of a key or by the manipulation of a knob or other suitable handle.

In one of its preferred, practical forms, a slide is contained within the lock casing and is adapted to be reciprocated in either direction by means of a cam adapted for operation, either by means of a knob associated therewith, or by a key operated barrel of the cylinder or pin lock. The knob and lock barrel are so associated with the door on which the lock is mounted, that a key may be employed to open the door from without, while the knob may be used to open the door from within. I preferably associate with the slide a guard, also preferably in the form of a secondary slide, mounted on the main slide, and adapted to cooperate with stops to normally lock the main slide in both its locking and unlocking positions.

The main slide is, in the preferred form of this invention, provided with one or more openings or apertures, which, when the lock is in unlocked position, are adapted to receive a corresponding number of hook shaped studs constituting a part of the keeper fixed on the door frame. These hooked shaped studs are so proportioned with respect to the slide openings, and the thickness of the slides, that when the studs of the keeper are in a position within the openings of the slide, said slide may be shifted to locking position wherein it will be caused to interlock or interfit with the hooked shaped studs, in such manner as to

preclude the separation of the parts until the slide has been shifted by means of the key or knob into an unlocked position.

The structure described is one which has been found highly practical, but the present invention is not limited to the precise details of construction referred to.

Features of the invention, other than those specified, will be apparent from the herein-after detailed description and claims, when read in conjunction with the accompanying drawings.

The accompanying drawings illustrate one practical embodiment of the invention, but the construction shown therein is to be understood as illustrative, only, and not as defining the limits of the invention.

Figure 1 is a perspective view showing the lock in unlocked condition and the keeper in a position to come into cooperative relation with the lock.

Figure 2 is a face view of the lock casing, showing the cover removed and the interior parts in unlocked positions.

Figure 3 is a view like unto Figure 2, but showing the parts in locked position.

Figure 4 is a section on the line 4—4 of Figure 3.

Figure 5 is an outside view of the cover plate; and,

Figure 6 is an inside view of the cover plate.

The invention consists, generally speaking, of two distinct parts or elements, namely, a keeper 1 and a lock 2. The keeper is adapted to be fixedly mounted on a door casing and to this end embodies an angular plate 3 adapted to be set in the edge of the door frame and secured in place by screws passed through countersunk holes 4 formed in the plate 3. The plate 3 is preferably in the form of a casting, integral with which is cast one or more hook shaped studs 5, two of which are shown for the purpose of illustration. These studs are set in vertical alinement and are separated by a narrow slot 6. A fillet 7 is preferably formed at the base of the studs so as to impart greater strength to the construction and eliminate the possibility of the studs breaking off the plate 3.

The lock 2 comprises a lock casing 8 of any suitable exterior shape or configuration. This casing may be made plain or ornate, and may, as well as the keeper, be made in

various sizes, depending upon the strength which it is desired that the lock shall have. One side of the casing is closed except for two openings 9 of a size and shape substantially the same as the heads of the studs 5 of the keeper and similarly positioned with respect to one another. The casing is moreover provided with countersunk holes 10 which extend directly through the same and through bosses 11 formed interiorly of the casing, so that bolts or screws may be passed through these holes for the purpose of securely mounting the casing on the inside of the door.

15 The other side of the casing is partially closed by means of a cover plate 12, shown in Figures 5 and 6, which cover plate extends substantially from a point back of the openings 9 to the opposite end of the casing.

20 This cover plate is normally secured in position by means of screws passed through the countersunk holes 13 in the back plate and threaded into tapped holes in bosses 14, cast interiorly of the casing 8.

25 The front wall of the casing is provided with an interior, flat face, over which a slide 15 is adapted to be slid back and forth longitudinally of the casing while guided for such movement between parallel guides 30 16 cast on said flat face.

Journalled for rotation in the front wall of the casing is an arbor 17, which extends through said front plate and carries at its outer end a knob 18 which may be grasped 35 and manually rotated. Interiorly of the front wall and spaced therefrom, said arbor carries a circular disc 19 and between the disc 19 and the front plate is positioned a cam 20, rigid with the arbor and preferably formed integral therewith. The disc 19 is also rigid with the arbor and its face opposite the cam 20 carries an upstanding fixed pin 21. This pin 21 is adapted for cooperation with a dog 22, the hub 23 of 40 which is journalled for rotation in the back plate 12. The hub 23 of the dog is positioned coaxial with the arbor 17 and a pin 24 extends from the dog and enters a hole in the center of the circular disc 19, so as 45 to maintain the parts coaxial. The rotation of the dog 22 is adapted to bring either one of a pair of shoulders 25 into engagement with the pin 21 to impart rotation to the cam.

50 This rotation of the hub 23 is adapted to be imparted by a key through the agency of a rotary lock barrel of the well known Yale or Corbin type, which rotary lock barrels are well known and in common use and need not be shown or further set forth in this description. They are all provided with a stem or rod of rectangular cross section and when used in conjunction with the present invention, this rod or stem is 55 adapted to enter a rectangular hole 26 in the outer end of the hub 23. In mounting the lock on the door, the conventional lock barrel is mounted on the outside of the door, the lock 2 of the present invention mounted interiorly of the door and the two connected 60 by the rectangular rod referred to, so that the cam may be turned from the outside of the door by means of a key associated with the lock, while said cam may be turned interiorly of the door from the inside of the door by means of the knob 18.

The cam 20 works in a cut out portion of the slide, which cut out portion has a curved edge 27. Through rotation of the cam 20, it is brought into engagement with the 65 curved edge 27 of the cut out portion and through this cooperation between the parts, sliding movement is imparted to the slide 15.

One end of the slide 15 is provided with 70 openings 28 adapted, when the slide is in unlocking position to register and coincide with the openings 9 formed in the front wall of the lock, so as to permit the passage of the studs 5 through the openings 28 and 90 9, when the parts are in these positions. The thickness of the slide is, however, so proportioned at that part thereof in which the openings 28 are formed, that if the slide is retracted, while the studs are in the position described, that portion of the slide between the openings 28 and the forward end of the slide will be retracted beneath the overhanging heads of the studs 5, as best shown in Figure 4. When this has been 100 accomplished, it will be apparent that the withdrawal of the studs is impossible since the studs and the sliding plate of the lock are interfitted or interlocked in such manner as to preclude separation of the parts and 105 consequent opening of the door until the locking plate of the lock has been retracted, either through the employment of the proper key from the outside of the door, or by manipulation of the knob 18 from the 110 inside of the door.

In practice, I have found that the employment of two studs produces an unusually strong, rigid and dependable construction, though, if desired, a single stud 115 or more than two may be employed.

The lock of the present invention may be employed as an entirety, as thus far described, the slide 15 being locked against inadvertent movement at both termini of 120 its travel by the cam 20, which, it will be noted from Figures 2 and 3, is, at these times, on dead centers. However, in order to assure a more permanent and positive locking of the slide 15, particularly by unauthorized persons, through the employment of a jimmy or the like, additional and positive locking means is preferably provided. This means may, in practice, conveniently partake of a form of a supplement. 125 130

tal slide 29, the lateral edges of which are dove-tailed into guide flanges 30, cast integral with the slide 15, as shown best in Figures 2, 3 and 4. The supplemental slide 29 is thus mounted on and carried by the main slide 15 and moves therewith, but, is, at the same time, mounted for sliding movement transversely of the main slide. The supplemental slide is bifurcated at one of its ends to provide legs 31, between which the cam 20 extends and with which legs are adapted for cooperation with fixed studs 32. A leaf spring 33 at all times presses against a pin 34 mounted on the supplemental slide 29 and serves to force the slide against the cam 20.

The parts are so organized and proportioned that when the slide 15 is in retracted unlocking position, as shown in Figure 2, with the cam 20 on dead center, the spring 33 will force the legs 31 into engagement with the forward edges of the stops 32, so that if attempt is made to move the slide by the application of force directly thereto, such movement will be arrested by the stops 32. On the other hand, if an attempt is made to move the slide 15 from the locking position of Figure 3 to the unlocked position of Figure 2, the legs 31 of the supplemental slide will engage with the rear edges of the stops 32 and such movement will be arrested. However, if the cam 20 is rotated by either the proper key or through the knob 18, such rotation of the cam will serve to shift the supplemental slide 29 against the tension of the spring 33 to withdraw the legs 31 of the supplemental slide from engagement with the studs 32. About the time the legs of the supplemental slide have been shifted free from the stops 32, the cam will engage with the edge 27 of the cut out portion of the main slide 15, so that further rotation of the cam will cause the movement of the main slide from locking to unlocking position or vice versa. As the main slide moves into this new position and comes to rest, the cam 20 comes on dead center and permits the supplemental slide 29 to be forced forward by the spring 33, so that its legs 31 will occupy locking positions with respect to the stop 32. It will be thus apparent that in either of the locked or unlocked positions of the main slide 15, said slide is doubly locked against movement by force applied directly thereto as by a jimmy or other burglar tool.

The lock of the present invention, as thus far described, is adapted for operation with both a key and a knob. This is the construction employed for outside doors and in similar environment where it is desired to open the door from both sides. A very satisfactory inside lock, however, or one operable only by a knob, may be produced by omitting from the construction described

the dog 22, its hub 26 and the pin 21, which parts are shown in Figures 4, 5 and 6. When these parts are omitted, the lock is controllable by the knob 18 only and when so constructed, may be used to advantage on 70 closet doors, dumb waiter shaft doors or for similar uses.

It will be further apparent that the knob may be omitted and the arbor so positioned that it will not extend through the front 75 wall of the casing, thereby providing a lock which may be operated only by a key.

It will be apparent from the foregoing description that the lock of the present invention is unusually simple in construction. 80 It embodies, in the main, but three relatively movable elements, namely, the locking slide, the supplemental guard slide and the cam for operating both of these slides. My experience with locks has convinced me that 85 locks embodying a number of pivots are unreliable and are adapted to stick or jam unless made with considerable care and properly fitted. In the lock of the present invention, there is not a single pivot and 90 the locking operation is carried out through the manipulation of cooperating slides with respect to a rigid keeper.

In the accompanying drawings, and in the foregoing detailed description, I have 95 set forth the lock of this invention in its preferred, practical form. I am aware, however, that the construction may be changed or modified in mechanical details, such as by the substitution of equivalents 100 without departing from the spirit of this invention, the scope of which is to be understood as commensurate with the appended claims.

Having thus fully described the invention, what I claim as new and desire to secure by Letters Patent is:

1. A door lock embodying a casing adapted to be mounted on one side of a door so as to project beyond the edge thereof and provided adjacent one end with an opening positioned beyond the edge of the door, a movable member within the casing and also provided with an opening, and means for moving said member to bring the opening of the member into and out of registration with the opening of the casing, in combination with a hook shaped keeper intended to be mounted on one side of the door jamb in the path of the opening of the casing and adapted, when the door is swung shut, with the opening of the movable member in registration with the opening of the casing, to pass through said opening and into the casing, whereupon the movement of said member will shift the same into a position wherein the openings are out of registration to cause the hook shaped keeper to hook over the movable member and preclude separation of the casing and keeper and keep the 130

door closed until the opening of the movable member is returned to registration with the opening of the casing.

2. A door lock embodying a casing adapted to be mounted on one side of a door so as to project beyond the edge thereof and provided adjacent one end with an opening positioned beyond the edge of the door, a movable member within the casing and also provided with an opening, and means for moving said member to bring the opening of the member into and out of registration with the opening of the casing, in combination with a hook shaped keeper intended to be mounted on one side of the door jamb in the path of the opening of the casing and adapted, when the door is swung shut, with the opening of the movable member in registration with the opening of the casing, to pass through said opening and into the casing, whereupon the movement of said member, will shift the same into a position wherein the openings are out of registration to cause the hook shaped keeper to hook over the movable member and preclude separation of the casing and keeper and keep the door closed until the opening of the movable member is returned to registration with the opening of the casing, and means for locking the movable member against movement except that imparted thereto by the operating means for said member.

3. A door lock embodying a casing adapted to be mounted on one side of a door to project beyond the edge thereof, a sliding member mounted to slide longitudinally of the casing and having a head substantially equal in width to the interior width of the casing, said head being provided with an opening, a keeper adapted to be mounted on one side of the door jamb and having a hook-shaped projection adapted, when the door is swung shut with the opening in the head in a predetermined position, and pass through and beyond the opening in said head, and means for shifting the head longitudinally of the casing to cause the head to interlock with the hook-shaped projection of the keeper.

5. 4. A door lock embodying a casing adapted to be mounted on one side of a door to project beyond the edge thereof and provided on both its front and back with juxtaposed openings positioned beyond the edge of the door, a sliding member operable within the casing and provided at one of its ends with an opening, means for sliding the

sliding member longitudinally of the casing to bring the opening of said member into and out of registration with the openings in the casing, and a keeper adapted to be mounted on the door jamb, provided with a projection having an enlarged head positioned in the path of the openings in the casing and adapted, when the door is swung shut with the opening of the casing and sliding member in registration, to pass through all of said openings, whereby the subsequent sliding of the sliding member longitudinally of the casing shifts the opening of said sliding member into a position out of alignment with the openings in the casing for the purpose of locking the sliding member to the keeper.

5. A door lock embodying a casing adapted to be mounted on one side of a door to project beyond the edge thereof and provided with juxtaposed openings in the front and back beyond the edge of the door, a keeper adapted to be mounted on the door jamb and provided with a hook-shaped projection adapted, when the door is swung shut, to pass through both openings of the casing with a portion of the keeper projection housed within the casing in concealed position, and a sliding plate positioned within the casing and adapted to be slid into position to interlock with the hook shaped keeper projection when said projection is extending through the openings in the casing.

6. A door lock embodying a casing adapted to be mounted on one side of a door to project beyond the edge thereof and provided in its front and back with juxtaposed openings, a keeper adapted to be mounted on the door jamb and provided with a projection having an enlarged head, which projection is adapted when the door is swung shut, to pass through both openings in the casing, the opening in the front of the casing being of substantially the same size and shape as the enlarged head of the keeper projection, whereby all of the keeper projection except the head is concealed within the casing when said projection is extending through the openings in the casing, and a sliding plate operable within the casing and adapted, through sliding movement, to interlock with the keeper projection for the purpose of locking the casing to the keeper.

In testimony whereof I have signed the foregoing specification.

JOHN DECKER.
